(57) **CLAIM**

The ornamental design for a display screen or portion thereof with transitional graphical user interface as shown and described.

DESCRIPTION

FIG. 1 is a first image of a first embodiment in a sequence for a display screen or portion thereof with transitional graphical user interface showing my new design;

FIG. 2 is a second image thereof;

FIG. 3 is a third image thereof;

FIG. 4 is a fourth image thereof;

FIG. 5 is a first image of a second embodiment in a sequence for a display screen or portion thereof with transitional graphical user interface showing my new design;

FIG. 6 is a second image thereof;

FIG. 7 is a third image thereof; and,

FIG. 8 is a fourth image thereof.

The even-length broken lines illustrate portions of a display screen and form no part of the claimed design.

The appearance of the figures sequentially transitions between FIGS. 1 through 4, and between FIGS. 5 through 8. The process or period in which one image transitions to another forms no part of the claimed design.
